By Atty. A.B. Stoughton.

United States Patent Office.

CHARLES BALLINGER, OF PITTSBURG, PENNSYLVANIA, ASSIGNOR TO
"McKEE & BROTHERS," OF SAME PLACE.

Design No. 4,419, dated October 18, 1870.

DESIGN FOR THE ORNAMENTATION OF GLASS-WARE.

The Schedule referred to in these Letters Patent and making part of the same

To all whom it may concern:

Be it known that I, CHARLES BALLINGER, of Pittsburg, in the county of Alleghany and State of Pennsylvania, have invented or produced a new and original Design for the Ornamentation of Table Glass-Ware; and I do hereby declare the following to be a full, clear, and exact description of the same, reference being had to the accompanying drawing, in which—

Figure 1 represents a glass dish-cover, with the ornamentation thereon.

Figure 2 represents a section through the cover, to show its outline.

The design or ornament in and on the glass-ware consists—

First, in the representation of a flying dragon, shown at A A A, which is molded in glass, and on the under side thereof.

Second, in a knob, by which said cover is raised from or replaced on the dish, consisting of a shell, B, of the snail, conoidæ, or cerites family or class, which

is represented as lying upon another shell, C, of the scallop kind or class.

These ornaments constitute the design.

Fig. 2 represents the elevation of the cover and the knob, which cannot be so clearly shown in the other figure.

The "flying dragons" are placed around the margin of the cover, or what might be termed the "bowl" of the cover, and the shell B is placed on the apex or crown of the cover or inverted bowl.

What I claim as a design for ornamenting glass-ware for table uses or purposes, is—

1. The flying dragons, as represented at A.
2. As an ornament for the knob-portion of the glass-cover, a shell, B, as described and represented.

CHARLES BALLINGER.
